(57) CLAIM

The ornamental design for a "bottle pack", as shown.

DESCRIPTION

FIG. 1 is a front view of a bottle pack;

FIG. 2 is a top plan view thereof;

FIG. 3 is a rear view of FIG. 1;

FIG. 4 is a bottom plan view of FIG. 1;

FIG. 5 is a right—side view of FIG. 1; and,

FIG. 6 is a left—side view of FIG. 1.

The broken line showing of buckles and bottle in FIGS. 1 through 6 is for illustrative purposes only and forms no part of the claimed design.
